BOTTLE WASHER

William P. Bigelow, Stockton, Calif.

Application March 13, 1937, Serial No. 130,714

2 Claims. (Cl. 141—7)

This invention relates to bottle washing machines and particularly to one for washing gallon and half-gallon bottles; or jugs as they are more commonly known, such as those in which wine, vinegar and other products are retailed. The machine is equally adaptable however with but slight change, for use in connection with ordinary shaped bottles of various kinds.

The major object of my invention is to provide a machine for the purpose by means of which the bottles or jugs may be washed, sterilized and rinsed, and the labels, if any, thereon soaked off, in a rapid and very efficient manner, and without any manual work being necessary other than to feed the bottles into the machine and remove said bottles therefrom when washed.

My improved washer is also very simple and relatively inexpensive and there is nothing to get out of order or give trouble. Also the machine, though relatively small and compact, is capable of handling a large number of bottles in a given time.

These objects I accomplish by means of such structure and relative arrangement of parts as will fully appear by a perusal of the following specification and claims.

In the drawings similar characters of reference indicate corresponding parts in the several views:

30 Figure 1 is a front elevation of the machine.

Figure 2 is a top plan view with the lids of the washing chamber or enclosure removed.

Figure 3 is a sectional elevation on the line 3—3 of Fig. 2.

35 Figure 4 is a fragmentary radial section on the line 4—4 of Fig. 2.

Figure 5 is a longitudinal section of the retaining and positioning unit and the bottle supporting spider.

40 Referring now more particularly to the characters of reference on the drawings, the apparatus comprises a circular casing having a floor 1 and an upstanding circular wall 2 of considerably greater depth than that of the bottles to be washed. The casing is supported a suitable distance from the floor on legs 3.

An inner endless wall 4 concentric with the wall 2 and spaced therefrom a distance considerably greater than the diameter of a bottle, is supported with its bottom in spaced relation to the floor by a spider 5. This spider is secured on an axial shaft 6 which is non-turnably mounted in a support 7 secured in fixed connection with the floor. A circular flange F substantially the same diameter as the inner wall 4 projects

upwardly from the floor with a watertight seal, terminating short of the bottom of the wall 4 for the purpose which will be seen. The top of the walls 2 and 4 are on the same level and are provided with inwardly projecting bands 8 forming ledges for the support of removable sectional lids 9.

An endless circular enclosure is thus formed within the casing, and in this enclosure the washing and sterilizing, label soaking and final 10 rising operations are performed in the proper sequence as will now be described.

Turnable on the shaft 6 between the spider 5 and the support 7 is another spider comprising a plurality of evenly spaced radial arms 10 which project through the band-like space between the wall 4 and flange F and into the washing enclosure. At their outer ends the arms support horizontal discs 11 each having a central opening 12 slightly larger than the diameter of the mouth 13 of a jug 14 as shown in Fig. 3. The jug engaging and centralizing fingers 15 are mounted on the discs and upstand from about the central openings in evenly spaced relation, having an outward flare to their upper ends. The flare or slope of the fingers is such that in this particular machine, gallon or half-gallon jugs (which are of different diameters) may be supported with equal efficiency. In both cases, the mouths of the jugs enter the disc openings 20 so that said openings, in conjunction with the fingers, maintain the jugs in the desired vertical inverted position.

At the front of the casing, the wall 2 is provided with a rectangular opening 16 of sufficient size to enable a jug to be easily placed on or removed from the above described supporting units. One disc at a time is removably engaged and held in a position convenient to the opening 16 by an arcuate saddle 17 having curved deflection lips 17a; the saddle being mounted on a horizontal stem 18 disposed radially of the shaft 6 and slidably in a sleeve 19 secured on the wall 2 below the opening. A spring 20 acts to yieldably urge the saddle against the adjacent peripheral portion of a disc 11. Since the spider upon which all the discs are mounted is a rigid unit, the holding of one disc also maintains all the others at predetermined stationary positions about the circular enclosure, and since all said discs are evenly spaced, they all in turn occupy identical stations in the casing.

Supported from the floor under the jug supports and extending about the enclosure for a portion of its circumferential extent from ad-

jacent one end of the opening 16 is a pipe 21. This is closed at its ends but has needle jets 22 on the top axially alined with the disc openings 12 when the discs are in said stationary position.

5 A sterilizing and washing solution is supplied to the pipe under pressure by means of a motor driven pump 23 which draws from a tank 24 mounted as a unit with the machine under the casing. Liquid from the jets ultimately falling 10 onto the floor is confined to that circumferential portion thereof along which the pipe 21 extends by transverse partitions 25. A drain pipe 26 depends from said portion of the floor over the tank, discharging into a removable screen tray 15 27 supported on the tank. The solution is maintained in a heated condition in the tank by a suitable circulating heater 28 mounted as a unit with and in close proximity to the tank.

Also connected to the pipe 21 and disposed on 20 opposite sides of and spaced from a jug when the latter is in a stationary position on a support some distance away from the opening 16 are vertical pipes 29. These have side jet openings fac- 25 ing each other to spray the opposite sides of the jug and thus effectively washing off any labels on the jug.

Beyond the pipe 21 there are one or possibly two idle positions of each jug, so that the solution can drain from the jugs before they are 30 rinsed. The rinsing of each jug in turn is effected, also mainly when the jugs are stationary, by means of an overhead spray rose 30 and a needle jet 31 alined with and under the corresponding supporting disc 11 (see Fig. 4). These 35 are connected to an ordinary cold water pressure pipe 32 having a hand valve 33 therein. A drain pipe 34 leads to the sewer from the corresponding portion of the floor.

Pairs of flexible vertically disposed rubber cur- 40 tains 35, which are deflected by engagement with a jug to let the latter pass, extend toward each other from the walls 2 and 4 at the opposite ends of the jug rinsing station to confine the splashing water. Another pair of similar curtains is 45 mounted adjacent the feed-in end of the washing enclosure, just beyond the adjacent end of opening 16, to prevent possible outward splashing of the sterilizing solution.

In operation, with the pump and heater run- 50 ning and with the solution spraying inwardly into the enclosure from the various jets 22 as well as from the spray pipes 29, the operator stands adjacent the opening 16 and places the jugs in turn on the supports, rotating the supporting spider by hand. Each time the spider is thus ro- 55 tated, it is only moved the distance between the adjacent jug supports (the saddle 17 of course making it easy to determine such movement) and if any rinsed jugs are in the machine they are 60 removed as they pass from behind the adjacent curtains.

As each jug is thus advanced into the washing enclosure it is subjected on the outside to the spray from the jets 22 during its movement be- 65 tween stationary positions, at which time the jets discharge directly into the jugs thoroughly wash- 70 ing and sterilizing the same. By the time each jug reaches the vertical spray pipes 29, its outside is thoroughly wet and any label thereon saturated and loosened, so that the forceful spray from said pipes 29 then washes the labels off. The jugs then subsequently pass to the rinser, as previously described, after which they may drain when at an idle station beyond the rinser, but before be- 75 ing removed. As stated, the spider is thus inter-

mittently rotated by hand, the length of the intermissions determining the thoroughness of the washing and other operations, such intermissions being utilized by the operator in removing washed jugs and placing others on the supports for 5 washing. Two or three jugs per minute however is the average speed of washing.

The sterilizing solution is used over and over 10 as many times as may be feasible, the screened tray catching any paper, etc. which may be washed off of the jugs, so as to prevent possible 15 clogging of the pump. When it is desired to remove any washed off labels which have not floated to the drain pipe, it is only necessary to remove the lid sections and reach down into the casing 20 from above.

From the foregoing description it will be readily seen that I have produced such a device as substantially fulfills the objects of the invention 25 as set forth herein.

While this specification sets forth in detail the present and preferred construction of the device, still in practice such deviations from such detail may be resorted to as do not form a departure 30 from the spirit of the invention, as defined by the appended claims.

Having thus described my invention, what I claim as new and useful and desire to secure by Letters Patent is:

1. In a bottle washing machine including an 35 enclosure forming a washing chamber, said enclosure having a bottle passage opening there- 40 through, a plurality of spaced bottle supporting units disposed in a row in the washing chamber, means in the chamber to wash bottles supported 45 on said units, means mounting said units for movement along the chamber, and means to con- 50 secutively and releasably locate the bottle sup- 55 porting units in position accessible from said bottle passage opening; said last named means comprising a disc included with each bottle support- 60 ing unit, a portion of the periphery of said discs 65 projecting clear of said mounting means, and a 70 spring pressed saddle mounted in connection with the enclosure in the path of said disc portions and arranged to frictionally and releasably 75 engage the same in consecutive order.

2. In a bottle washing machine including an enclosure forming a washing chamber, said en- 50 closure having a bottle passage opening there- 55 through, a plurality of spaced bottle supporting units disposed in a row in the washing chamber, means in the chamber to wash bottles supported 60 on said units, means mounting said units for movement along the chamber, and means to con- 65 secutively and releasably locate the bottle support- 70 ing units in position accessible from said bottle passage opening; said last named means comprising a disc included with each bottle support- 75 ing unit, a portion of the periphery of said discs 80 projecting clear of said mounting means, a saddle 85 disposed in the path of said disc portions, the saddle having an arcuate face corresponding to the peripheral curvature of said disc portions, curved deflection lips extending from the ends 90 of the saddle to a point out of the path of move- 95 ment of said disc portions, a stem on the saddle and projecting therefrom at right angles to the axes of the discs a sleeve mounted on the enclo- 100 sure and slidably supporting the stem, and a compression spring disposed in the sleeve and arranged to urge the stem and saddle in a disc engaging direction.

WILLIAM P. BIGELOW.
